Primary Examiner—Bruce W. Dunkins*Assistant Examiner*—Jeffrey Asch*Attorney, Agent, or Firm*—Stetina and Brunda[57] CLAIM

The ornamental design for a storage cart for an automobile hardtop, as shown and described.

DESCRIPTION

FIG. 1 is a front, top and right side perspective view of a storage cart for an automobile hardtop showing my new design;

FIG. 2 is a right side elevational view, the left side being a mirror image thereof;

FIG. 3 is a rear elevational view; and

FIG. 4 is a bottom plan view thereof.

FIGS. 2-4 have been shown on a reduced scale with respect to FIG. 1.

FIG. 1

FIG. 4
